W. N. BEST.
OXIDATION OF FINELY SUBDIVIDED MATERIAL.
APPLICATION FILED FEB. 8, 1919.

1,397,791.

Patented Nov. 22, 1921.

UNITED STATES PATENT OFFICE.

WILLIAM N. BEST, OF BROOKLYN, NEW YORK.

OXIDATION OF FINELY-SUBDIVIDED MATERIAL.

1,397,791.

Specification of Letters Patent.

Patented Nov. 22, 1921.

Application filed February 8, 1919. Serial No. 275,682.

To all whom it may concern:

Be it known that I, WILLIAM N. BEST, a citizen of the United States, and a resident of Brooklyn, in the county of Kings and 5 State of New York, have invented certain new and useful Improvements in the Oxidation of Finely-Subdivided Material, of which the following is a specification.

This invention relates to the oxidation of 10 pulverulent or other finely-sub-divided material and has for its main object to more effectively bring the finely sub-divided material into intimate contact with a gaseous heating medium and a gaseous oxidizing 15 agent.

So far as my improved apparatus is concerned, I do not wish to be limited to any particular finely sub-divided material nor to the character of the resultant product of 20 the process employed. In carrying out my invention I use a burner or liquid fuel atomizer which will give a substantially flat spray of vapor of a liquid or semi-liquid fuel such as oil or tar. The atomizing or 25 vaporizing of the liquid fuel and the projecting of it in the form of a flat spray is secured by means of an atomizing jet of compressed air or steam. Air for supporting the combustion of this liquid fuel is 30 delivered preferably under comparatively low pressure adjacent to the spray so as to produce a substantially flat fan-shaped flame. The material which is to be oxidized is delivered mechanically as for instance, by 35 gravity through a chute, trough, or conduit and in suitably regulated quantities. The point of delivery of the finely sub-divided solid material is directly above the flat fan-shaped flame so that said material falls into 40 and through the flame and is highly heated by the latter and is oxidized by the current of air which is supplied not only for such oxidation but for the supporting of the combustion of the finely sub-divided liquid 45 fuel.

One of the main objects of my invention is to more effectively utilize coal dust, culm, screenings, or other solid fuel existing in large quantities in a finely sub-divided state. 50 I am aware that such finely sub-divided solid fuel has been used in furnaces by blowing or spraying it into the combustion chamber in which a fluid fuel is also burned but so far as I am aware no one has heretofore proposed permitting such finely sub-divided solid material to fall through a fan-

shaped flame of a liquid fuel atomized by a gaseous medium so that the solid fuel is both highly heated and the combustible portions completely oxidized. With this improved 60 arrangement, the furnace may be first heated solely by the burning of the spray of liquid fuel and the additional fuel to produce the additional heat may be delivered either continuously or at such times as may be desired, 65 to the fan-shaped flame.

A further object of my invention is to provide a simple, effective, and inexpensive process for the oxidizing of such finely sub-divided materials as result in solid oxids 70 rather than gaseous oxids like carbon-dioxide. My invention is particularly applicable for use in the producing of copper 75 oxid from finely sub-divided copper. The finely sub-divided copper or other metal or material to be oxidized is delivered to and permitted to fall through the fan-shaped flame and the oxidizing air and is completely, thoroughly and uniformly oxidized at high temperature before it falls to and 80 collects on the bottom of the furnace or in other suitable collection chambers. Materials other than copper which produce solid oxids and materials other than coal dust which produce gaseous oxids, may be employed in my improved apparatus and in 85 carrying out my improved process.

In the accompanying drawings I have illustrated certain essentials of an apparatus adapted to carry out my improved process. 90

In these drawings:

Figure 1 is a central vertical section through a portion of an apparatus showing the burner or liquid atomizer in one position, and

Fig. 2 is a view similar to a portion of Fig. 1 but showing the burner or atomizer in an inverted position.

In these drawings, I have illustrated a portion of a furnace chamber having a combustion chamber 11. This furnace may be of any desired form, shape, or character, depending entirely upon the material to be heated by the heat of the furnace or the material to be oxidized in the flame. Opposite to the entrance to the combustion chamber I employ a burner or atomizer 12 having a delivery passage 13 for oil, tar, or other liquid or semi-liquid fuel and a passage 14 for steam, compressed air, or other 105 gaseous or fluid atomizing medium. The outlets from these passages are so juxta-

posed that the escape of the atomizing medium delivers the liquid fuel in a substantially fan-shaped sheet or spray. The outlet from the passage 14 is formed between the 5 body of the burner and an adjustable member 15. The two passages may be connected up to suitable sources of supply of the two fluid mediums by pipes 16 and 17. I do not here claim anything as novel in this 10 form of burner or liquid fuel atomizer as it may be constructed in accordance with my various prior patents, as for instance, 708,453 of September 2, 1902, and 752,195 of February 16, 1904. Below the burner or 15 atomizer is a nozzle 18 for delivering the low pressure combustion supporting gaseous medium, such as air.

In connection with this mechanism, I employ a receptacle 19 which may be in the 20 form of a hopper or of any desired shape, size, or form and from which a conduit 20 extends to a delivery nozzle or outlet 21. This is positioned slightly above the plane 25 of the fan-shaped flame, said plane being indicated approximately by the line A in Figs. 1 and 2. This nozzle 21 is also disposed slightly beyond the outlet for the expansive medium which delivers and distributes the liquid fuel. In order to secure 30 a substantially continuous delivery of the finely sub-divided material, such as coal dust, metallic copper, or other oxidizable material, to break up any large chunks in the receptacle, and to keep the conduit from 35 clogging up, I provide some suitable form of mechanical agitating and feeding means. Merely as an example of such means, I have shown a reciprocating plunger 22 connected to an eccentric strap 23 of an eccentric 24, 40 which latter is secured to and rotated by a shaft 25 above the hopper. The lower end of the rod 22 may be roughened or recessed or provided with pockets or other surface irregularities and terminates within the portion 45 of the conduit 20 connected to the hopper. The rotation of the eccentric gives the rod both a reciprocating movement within the conduit and a slight lateral movement so as to effectively deliver material from the 50 hopper to the conduit. The rate of delivery may be controlled not only by varying the speed of the shaft 25 but also by controlling the inlet opening to the pipe 20. I have shown a pair of closure sections 55 26—26 slidably mounted on the bottom of the hopper upon opposite sides of the rod 22, and extending partway across the inlet end of the conduit 20. These closure sections may be adjusted toward and from each 60 other in any suitable manner, as for instance, by screw threaded engagement with shaft sections 27 having operating handles or cranks 28 and held against longitudinal movement by nuts upon opposite sides of 65 supporting brackets 29.

The relative positions of the burner and the delivery nozzle for the solid material may be varied dependent upon the character of the furnace and the character of the liquid and solid materials oxidized therein. 70 In Fig. 2 I have shown a construction involving the same structural elements as in Fig. 1 but have shown the burner or atomizer inverted so that the atomizing gaseous medium is delivered across the open 75 upper end rather than the open lower end of the liquid fuel delivery passage. In many respects this is the preferable positioning of a burner of this character.

Materials of various different states of 80 sub-division may be employed, the fineness of the material or the regularity and size of the particles being dependent to a certain extent upon the nature of the material. If the solid material is to be oxidized in 85 order to produce heat, I preferably pulverize it or screen it to pass through a 100, 150, or 200 mesh but coarser or finer material may be employed.

Although I have shown the solid material 90 delivered to the flame or liquid fuel spray solely by the action of gravity, it will of course be understood that other delivering means might be employed. Although under ordinary circumstances the combustion supporting gaseous medium is air under comparatively low pressure, as for instance, from a blower, yet it will of course be understood that other means for supplying such combustion supporting medium might be 95 employed or that the fan-shaped flame might be so positioned that a sufficient amount of combustion supporting air would be automatically taken direct from the atmosphere without the necessity for the delivery nozzle 18. Under some special circumstances I might employ oxygen of any 100 desired purity instead of ordinary air.

Having thus described my invention what I claim as new and desire to secure by Letters Patent is:

1. The process of oxidizing pulverulent or other finely sub-divided solid material, which consists in continuously delivering a liquid fuel, expanding a gaseous medium 115 across the liquid fuel outlet to form a substantially flat fan-shaped spray of liquid fuel, delivering the pulverulent or other finely sub-divided solid material to a point above said fan-shaped spray with the latter 120 in a state of ignition and from which said material may fall by gravity into and through the zone of combustion, and delivering air closely beneath and substantially parallel to the spray to support combustion of the liquid fuel and oxidation of the solid material.

2. The process of producing heat, which consists in delivering a substantially flat fan-shaped spray of liquid fuel by means of 130

a vaporizing jet of gaseous medium, supplying combustion supporting air to the spray whereby a substantially flat fan-shaped flame is produced when said spray 5 is ignited, and delivering finely sub-divided coal to said fan-shaped flame.

3. The process of producing heat which consists in delivering a substantially flat fan-shaped spray of liquid fuel by means 10 of a vaporizing jet of gaseous medium, sup-

plying combustion supporting air to the spray whereby a substantially flat fan-shaped flame is produced when said medium is ignited, and permitting finely sub-divided coal to fall by gravity into or through said 15 flame.

Signed at New York city, in the county of New York and State of New York, this 7th day of February, A. D. 1919.

WILLIAM N. BEST.
